UNITED STATES PATENT OFFICE.

SAMUEL B. DRUCKER, OF BROOKLYN, NEW YORK.

MACHINE FOR MAKING MAYONNAISE.

Application filed September 30, 1926, Serial No. 138,615. Renewed July 14, 1927.

This invention relates to mayonnaise making machines, and embodies the subject-matter shown, described, but not claimed in my application executed and filed of even date 5 herewith.

The object of the invention is to provide an improved means for clamping and holding firmly and rigidly the stationary member employed in connection with a revolvable 10 container in machines in making mayonnaise.

Other objects of the invention will appear more fully hereinafter.

The invention consists substantially in the 15 construction, combination, location, and relative arrangement of parts, all as will be more fully hereinafter set forth, as shown in the accompanying drawing, and finally pointed out in the appended claims.

20 Referring to the drawing,—

Figure 1 is a view in elevation, parts broken out, and in vertical central section, showing a structure of machine for making mayonnaise employed in connection with 25 my invention.

Figure 2 is a view in section on the line 2, 2, Fig. 1, looking in the direction of the arrows, illustrating a form of clamping and supporting means embodying my invention.

30 Fig. 3 is a broken detail view in section on the line 3, 3, Fig. 2, looking in the direction of the arrows.

Fig. 4 is a broken detail view in section on the line 4, 4, Fig. 2, looking in the direction of the arrows.

35 Fig. 5 is a view in perspective showing a stationary member for use in a mayonnaise making machine and the application thereto of clamping and supporting means embodying my invention.

40 The same part is designated by the same reference numeral wherever it occurs throughout the several views.

In its essential features the mayonnaise 45 making machine to which my invention is applied, consists of a container which is mounted to revolve axially, and into which protrudes or extends a detachable stationary held frame which cooperates with the 50 revolving container to effect the mixture and emulsification of the constituents of the mayonnaise batter. The present invention has particular reference to means for efficiently clamping and holding the detachable frame member.

55 Referring to the drawing,—7 designates

a suitable stand, and 8 a motor mounted therein, which is arranged to rotate a supporting table 9, upon which may be mounted for axial rotation therewith a container 10. 60

In the drawing, the container 10 is composed of wood, preferably made of slats as customarily employed in making barrels, as clearly shown by the shade lines in Figures 1 and 2. A supporting platform 12 is carried by standards 11 mounted upon the base 7, said platform 12 being disposed above the container when the latter is positioned upon the revolving table 9. Depending from the platform 12 is a flange portion 13 to 70 which is detachably clamped the clamp plate 15. Any suitable means may be employed for detachably clamping the clamp plate 15 to the depending portion 13. A clamp bolt 14 is shown for this purpose, the threaded 75 end of which is designed to be received in a threaded opening formed in the depending portion 13, with the clamp plate 15 held between said depending portion 13 and a shoulder 17 formed on the clamp bolt 14. 80

If desired, centering studs 16, carried by the plate 15, may engage in seats formed in the depending portion 13 for this purpose. The stationary frame which extends into and cooperates with the revolving container 10 is 85 of generally rectangular shape, and includes the upper and lower members 18, 19, connected together by the side members 10 and the intermediate members 21. The parts so far described in the specific details thereof form no part of my present invention. 90

The upper member 18 of the stationary frame is formed with a vertical slot to receive therein the clamp plate 15, said plate being clamped in said slot by means of clamp bolts 23, which pass transversely through the walls of the slot in the upper member 18 of the stationary frame, and through elongated openings 22 in the clamp plate 15. In order to efficiently and rigidly clamp the stationary member to the clamp plate, it is desirable to constitute the side walls of the slot in said member 18 in effect spring clamping jaws. To accomplish this purpose, the member 18 is formed with kerfs 24, which extend into the end edges of the slot, which receive the plate 15. In practice I prefer to dispose the kerfs 24, which respectively communicate with the edges of the slot in the member 18, at opposite sides of the plate 15, and at 105 diametrically opposite corners of said slot. By this construction, the side walls of the

slot are constituted in effect spring clamping jaws, which efficiently clamp and grip the clamp plate 15 when the nuts on the clamping bolts 23 are turned up to draw the walls 5 of the slot together into clamping relation with respect to the plate 15. The elongated slots 22 in plate 15 afford a means for securing a desirable relative adjustment of the frame member 18 in clamp plate 15 so as to 10 properly and accurately dispose said frame in proper relation with reference to the container 10 into which it extends. With the frame member 18 and plate 15 properly adjusted, the one to the other, and efficiently 15 clamped together by the spring jaws afforded by the side walls of the slot in member 18 which receives the clamp plate, the entire structure of frame 18, 19, and the connected parts, may be quickly and easily 20 clamped in rigid and stationary position by means of the clamp bolt 14, or detached, by removing said clamp bolt so as to permit the removal of said frame.

The process, involving the use of the apparatus herein disclosed and claimed, is 25 claimed in my co-pending application 550, 681, filed April 8, 1922.

Having now set forth the objects and nature of my invention, and a structure embodying the principles thereof, what I claim 30 as new and useful and of my own invention and desire to secure by Letters Patent is,—

1. In a machine for making mayonnaise, an emulsifying member having a slotted portion, and means to detachably clamp and hold said member stationary when in working position, including a clamp plate extending into said slot, said member having oppositely disposed kerfs respectively communicating with the edges of said slot, clamp bolts passing through said plate and the side walls of said slot to clamp the parts together, and means to detachably support said plate.

45 2. In a machine for making mayonnaise, an emulsifying member having a slotted por-

tion, and means to detachably clamp and hold said member stationary when in working position, including a clamp plate extending into said slot, said member having spring 50 acting kerfs respectively communicating with diagonally opposite corners of said slot, clamp bolts passing through said plate and the side walls of said slot to clamp the parts together, and means to detachably support 55 said plate.

3. In a machine for making mayonnaise, an emulsifying member having a slotted portion, and means to detachably clamp and hold said member stationary when in working position, including a clamp plate extending into said slot, said member having oppositely disposed kerfs respectively communicating with the edges of said slot, clamp bolts passing through said plate and the 60 side walls of said slot to clamp the parts together.

4. In a machine for making mayonnaise, an emulsifying member having a slotted portion, and means to detachably clamp and hold said member stationary when in working position, including a complementary member extending into said slot, said first member having spring acting kerfs respectively communicating with diagonally opposite corners of said slot, clamp bolts passing through said second member and the side walls of said slot to clamp the parts together.

5. In a machine for making mayonnaise, an emulsifying member having a slotted portion, and means to detachably clamp and hold said member stationary when in working position, including a complementary member extending into said slot, said first member having spring acting oppositely disposed portions forming the side walls of said slot, clamp bolts passing through said second member and the side walls of said slot to clamp the parts together.

In witness whereof I have hereunto signed 90 my name this 29th day of September, 1926.

SAMUEL B. DRUCKER.
